UNITED STATES PATENT OFFICE.

WALTER P. MURPHY, OF ST. LOUIS, MISSOURI.

BRACKET FOR UNCOUPLING-LEVERS.

1,031,810.

Specification of Letters Patent.

Patented July 9, 1912.

Application filed September 21, 1910. Serial No. 583,119.

To all whom it may concern:

Be it known that I, WALTER P. MURPHY, a citizen of the United States, residing at St. Louis, in the State of Missouri, have 5 invented certain new and useful Improvements in Brackets for Uncoupling-Levers, of which the following is a specification.

The bracket commonly employed on railroad cars to support the rod of uncoupling levers is rigidly secured, in its entirety, to the car structure in such manner that it is necessary to remove the entire bracket in making repairs or replacing the rods, and the removal of the bracket is somewhat difficult by reason of the fact that the bolts and other securing means have become rusty.

The object of my invention is to overcome the difficulties heretofore experienced 20 in brackets of this character by making the bracket in two parts.

In the drawings, Figure 1 is an end elevation of a car with my invention secured thereto; Fig. 2 is a top plan view of one 25 of the brackets detached; Fig. 3 is a side elevation of the same; Fig. 4 is a sectional view on the line 4—4, Fig. 2, and Fig. 5 is a rear elevation of the bracket.

The numeral 1 represents a car of any 30 approved type, parts being broken away, and 2 the end sill which may be of any approved pattern, whether of metal or wood.

The numeral 3 designates the coupler head, 4 the locking pin and 5 an unlocking 35 rod which may be of any approved pattern.

6 is the operating handle of the rod 5. The inner end of the rod, as will be understood, is bent at right angles to the rod and projects out over the locking pin 4 to which 40 it is secured directly or by means of a link or chain.

My improved bracket consists of the base plate 7 which may be constructed with any desirable contour.

45 The numeral 8 designates bolt openings or holes in each end, through which the bolts, screws or other securing devices are passed to secure the base plate rigidly to the end sill of the car. This plate is provided with a lug or boss 10 having a concaved bearing face or seat 11, in which the rod 5 is adapted to be seated. As shown more clearly in Fig. 2, the boss or lug 10 is provided with a central slot 12 which 50 extends through the base plate 7.

The numeral 13 designates a hole extend-

ing through two opposite walls of the lug 10 which are adapted to receive the cotter pin 14.

The numeral 15 designates slots extending through the base plate on two diametrically opposite sides of the boss or lug 10.

The numeral 16 designates a U-shaped strap provided near its ends with cotter pin openings 17 which, when the strap is properly adjusted on the base plate 7, register with the openings 13 in the boss or lug 10. As shown in Fig. 4, the ends of the strap 16, when the strap is in proper position on the base plate, project through the slots 15 and are flush with the bottom face of the base plate 7.

In practice, the base plate 7 is secured by the bolts 9 to the end sill of the car and the rod 5 is placed in the concaved seat 11. 75 The strap 16 is then placed over the rod and completes the bearing for the rod in conjunction with the concaved seat 11, the ends of the strap projecting through the slots 15 flush with the under face of the base plate 7. The cotter pin is then passed 80 through the openings 17 in the strap and the hole 13 in the lug 10, thus securing the strap firmly and securely to the base plate. The split end of the cotter pin is then spread 85 as is usual with such pins, whereby the parts are firmly locked together against displacement.

In the event that it is desired to remove the rod 5 for any purpose whatever, this 90 may be easily accomplished by straightening the ends of the cotter pin, removing the cotter pin and the strap 16, whereupon the rod is free to be removed from the car without disturbing the permanent fastenings securing the base plate of the bracket to the car.

Having thus described my invention, what I claim as new therein and desire to secure by Letters Patent is:—

1. A bracket for an uncoupling lever for cars, including a base having a lug terminating in a concaved bearing and provided with an opening extending therethrough between said bearing and the base, a strap extending over the lug and forming therewith a circular bearing and provided with openings registering with the opening in the lug, and a pin passing through said openings securing the strap to the lug. 105
2. A bracket for an uncoupling rod, comprising a base, a lug on said base, a concave 110

seat on the end of said lug, said base having slots on two opposite sides of said lug, a U-shaped strap constructed to fit over said lug with its ends projecting through the slots in the base and a securing member passing through the said lug and strap detachably securing the strap to the base.

In testimony whereof I affix my signature in presence of two witnesses.

WALTER P. MURPHY.
